UNITED STATES PATENT OFFICE

2,215,378

SIGNALING DEVICE

Charles H. Scott, Queens Village, N. Y., assignor
to The Dorr Company, Inc., New York, N. Y.,
a corporation of Delaware

Application December 31, 1936, Serial No. 118,544

6 Claims. (Cl. 210—3)

The present invention relates to signaling devices, and more particularly to an improved signaling device adapted to sound or display a signal or alarm upon the failure of machinery to function properly.

The present invention is particularly adapted for use in connection with mechanically cleaned sedimentation tanks, and more specifically for use with machinery for operating the raking mechanism of clarifiers of sewage disposal systems. In such systems it is essential that the mechanism operate continuously and at a constant rate of speed. A shut down of the mechanism may result in stoppage of the sewage disposal process, with a consequent menace to the health of the community served thereby.

In carrying out the present invention, means controlling a signaling device, either visual or audible, is in turn controlled by the machine with which the means is associated. Preferably the signal controlling means is provided with electric circuit control means operated by means controlled by the speed of operation of the machine with which it is associated.

The design and arrangement of the device is characterized by its special application to center pier sedimentation tanks; that is to say, the arrangement according to this invention takes advantage of the center pier found in large sedimentation tanks and of a sediment raking construction which rotates about the center pier and which derives support therefrom. A suitable rotary circuit controlling or signaling or alarm device has fixed relationship with or is mounted upon the center pier, and the necessary rotation is imparted to it by virtue of the rotation of the sediment raking construction from the inner end thereof.

Accordingly, one group of features relates to the arrangement of the device with respect to its stationary mounting upon the center pier and with respect to its driving relationship with the rotary raking construction. Another group of features relates to specific improvements in the construction of the rotary switch device proper.

The device according to the invention is responsive to the travelling speed of a rotary raking mechanism which is supported upon and rotates about a center pier, and which raking mechanism is traction driven in the sense that tractive power is applied to the outer end portion of an arm member extending from the central portion of the rotary mechanism. In other words this is a traction driven machine of the type exemplified in the patent to S. I. Bousman #1,741,

498. It is this type of a traction driven machine with which the speed responsive device is combined according to the invention.

The invention, in the present disclosure, is designed to maintain quiescent an electric circuit controlling a signal device as long as the machine with which it is associated maintains a fixed minimum speed, and to operate the signal device operating circuit when the speed of the machine falls below the minimum specified. The present invention however, is broad enough in scope to embrace an embodiment in which the signaling device is operable when the speed of the machine with which it is associated exceeds a specified maximum.

A feature of the invention is a device for controlling a signal device when the speed of a machine with which it is associated varies from a specified constant.

A feature of the invention is a device for operating a signal device when the speed of a mechanism is reduced below a specified minimum.

A feature of the invention is a device for controlling an energizing circuit for a signal device upon a lowering of the speed of the device.

In the accompanying drawings:

Fig. 1 is a plan view of the turntable of the clarifier of a sewage disposal system to which the present invention has been applied.

Fig. 2 is a side elevation of the structure illustrated in Fig. 1, showing the same in position on a turntable base.

Fig. 3 is an end elevation of Fig. 2.

Fig. 4 is a sectional elevation, on the line 4—4 of Fig. 1, on an enlarged scale.

Fig. 5 is a section, taken on the line 5—5 of Fig. 4.

Fig. 6 is a sectional plan view, taken on the line 6—6 of Fig. 4.

Fig. 7 is a sectional elevation, taken on the line 7—7 of Fig. 5.

Fig. 8 is a front elevation of the casing of the device, showing the rotating element of the device, the cover of the casing being removed, and with the circuit closing liquid shown in normal position, and

Fig. 9 is a view, similar to Fig. 8, showing the circuit closing liquid in position to cause operation of the signal device.

Referring to the drawings, 10 designates a pier, preferably of concrete or masonry, and ordinarily located at the center of a clarifier tank of a sewage disposal system. Mounted on the pier 10 is a turntable base 11 and on which is rotatably mounted a turntable 12. Cooperating bearing 55

members 13 and 14 respectively formed on the turntable base 11 and turntable 12, having balls 15 therebetween, as shown in Fig. 2, provide convenient antifriction means for permitting easy 5 rotary movement of the turntable 12.

On the top of the turntable 12, and at the ends of a diameter, are aligned bearings 15a, and in which is rotatably mounted a shaft 16. At each 10 end of the shaft 16 and at the periphery of the turntable 12 are secured supporting rollers 17 and on which ride longitudinal members 18 of a reciprocating framework 19. The framework 19 carries oscillating arms for raking the corners of the clarifier tank, as fully described in the patent 15 to S. I. Bousman, No. 1,741,498, dated December 31, 1929.

Extending outwardly from diametrically opposite points on the turntable 12 are arms or brackets 20, and at the free ends of such arms or 20 brackets are rotatably mounted, on vertical shafts 21, the guide rollers 22. These guide rollers 22 engage with the vertical inner surfaces of the longitudinal members 18 of the reciprocating framework 19 and, with the supporting rollers 17, 25 serve to maintain the turntable 12 in operative relation with the framework during the reciprocating movement thereof.

One end of the reciprocating framework 19 is 30 driven by any suitable means, and is constrained to follow the contour of the periphery of the tank. As the tank, in the present instance, is non-cylindrical, there results a reciprocating movement of the framework 19, and the framework acts to 35 rotate the turntable 12 on the base 11.

The tank may be of relatively large dimensions, with correspondingly large dimensions of the reciprocating framework 19. The rate of rotation of the framework 19 and turntable 12 is therefore relatively low, but must be relatively 40 constant, and therefore constant watch must be maintained to control the rate of movement, or signal control means utilized to inform an attendant when the speed of rotation falls below a certain predetermined minimum.

The present invention contemplates an improved signal control means, and such a means is disclosed in operative relation with the structure above described.

Secured to the turntable base 11 by bolts 23 is 50 a casing 24 provided with a removable cover 25. Within the casing 24 are aligned bearings 26 in which is rotatably mounted a shaft 27 carrying a bevel pinion 28. The shaft 27 extends outwardly 55 through an opening in the casing 24 and through an opening 29 in an impeller housing 30, and which impeller housing is secured to the casing 24 by bolts 39. The casing 24 is oil tight, and is provided with a plug 31a through which oil may be withdrawn from the casing. Also the hole 29 60 in the impeller housing is provided with an oil seal bearing 31 for the shaft 27, so constructed as to prevent leakage of oil from the casing 24 through the hole 29.

The cover 25 of the casing 24 has rotatably 65 mounted therein a vertical shaft 32 which, when the cover 25 is secured in position on the top of the casing, has its lower end supported in a bearing 33 in the bottom of the casing. Secured to the shaft 32, adjacent to the under face of the cover 25, is a bevel gear 34 which meshes with, and drives, the bevel pinion 28, and therefore the shaft 27.

The shaft 32 has secured to its top end a pinion 35 forming part of a train of gears. Another pinion 36 of such train of gears meshes with and is 70

driven by a ring gear 37 secured to the turntable 12 by bolts 38. As the turntable 12 rotates, the shaft 27 is caused to rotate in the direction of the arrows shown in Figs. 5, 8 and 9 and at a rate of speed determined in accordance with the desired 5 normal speed of rotation of the turntable 12. The shaft 27 operates circuit controlling means for a signal device, as will be hereinafter described.

It is important to note a relationship and arrangement of parts that exist in the special combination of a suitable switch device with respect to the center pier of a sedimentation tank and with respect to the rotary rake construction revolving about the pier. It is also noteworthy that 15 a rotary switch device is stationary with respect to and upon the pier and is gear driven through the rotation of the rake construction.

The impeller housing 30 is provided with a circular recess 40 on its front face in which is 20 housed an impeller 41. The impeller or scoop wheel 41 is secured to the outer end of the shaft 27 and rotates therewith. On the front, or outer, face of the impeller 41 are formed a plurality of recesses or radially extending cavities 42, the depth of such cavities increasing from the center of the impeller 41 toward the periphery thereof. The scoop wheel or impeller 41 in the present embodiment is shown to consist of a hub portion 30 41a; a rim portion 41b; radial wall portions 41c extending between the hub and the ring portion, and a uni-lateral disc portion 41d which interconnects the hub portion, the rim portion and the radial wall portions of the impeller 41. The 35 rim portion 41b has a substantially cylindrical outer face which merges into the disc portion 41a by way of a rounded transitional portion 41e. The lower portion of the circular recess 40 of the impeller housing 30 is cut away, as indicated by 40 the numeral 43, and in such cut away portion is placed a felt dam 44, against the outer face of which bears the rear or inner face of the impeller 41.

The open front of the impeller casing is closed 45 by a cover 45. The cover 45 is secured to the open end of the casing by bolts 46, a rubber gasket 47 being interposed between the casing and cover. As thus constructed, the impeller casing and cover 50 constitute a fluid-tight chamber for a body of mercury 48. The mercury 48 is inserted into the fluid-tight chamber through a passage 49, closed by a screw plug 50.

Formed in the inner face of the cover 45, and in vertical alignment with the felt dam 44, is a 55 rectangular recess 51 in which, as a close sliding fit, is placed an adjusting block 52 of any suitable material, such as "micarta." The adjusting block 52 is movable toward and from the face of the impeller 41 to provide an orifice or gap for regulating the flow of mercury 48 back into the body 60 of such mercury as the same is carried upwardly by the depressions 42 in the impeller as such impeller rotates.

Extending through the cover 45 into the recess 51 and screwing into the adjusting block 52 is an adjusting screw 53. Above and below the adjusting screw 53 and screwing through the cover 45 are adjusting screws 54, the inner ends of which engage with the adjusting block 52. The adjusting screws 54 are provided with lock nuts 55. Between the head of the adjusting screw 53, the lock nuts 55 and the outer face of the cover 45 are washers 56. By the use of the adjusting screws 53 and 54 the orifice or gap between the cover 70 75 and

ating faces of the impeller 41 and adjusting block 52 may be adjusted to control the rate of flow of the mercury 48 back to the bottom of the casing 30.

Surrounding the adjusting screws 53 and 54 and formed integral with the cover 45 is a terminal box 57. The open end of the terminal box is closed by a cover 58, secured to the terminal box by bolts 59, a gasket 60 being interposed between the terminal box and cover.

The terminal box 57 houses the adjusting screws 53 and 54 of the adjusting block 52, and also houses the terminal contacts and a portion of the wiring for the control circuit of a signal device. In the drawings one of such terminals is shown as a ground contact and comprises a screw 61 threaded into a boss 62 formed integral with the cover 45. On the screw 61 is a washer 63 and between the washer 63 and the face of the boss 62 is clamped one end of a conductor 64.

The other of such terminals comprises a screw 64 extending through a perforation 65 in the cover 45, and having its head lying substantially flush with the inner face of the cover 45. The screw 64 extends through the blocks 66 of insulating material and thus is maintained out of electrical engagement with the cover 45. A nut 67 on the threaded portion of the screw 64 holds the screw in fixed position in the cover 45, and a second nut 68 on the threaded portion of the screw 64 acts as means for clamping the end of a conductor 69 in engagement with the screw.

Screwed into a threaded hole in one of the walls of the terminal box 57 is a conduit 70 through which the insulated conductors 64 and 69 are led to any suitable source of power and actuating instrumentalities for controlling the operating circuit for a signal device.

Referring to Figs. 8 and 9 the conductor 64 is shown connected to one end of an electromagnet 71, the other end of which is connected to a terminal of a source of power 72. The conductor 69 is connected to the other terminal of the source of power. Associated with the electromagnet 71 is a pivoted armature 73 provided at its free end with a contact plate 74 insulated from the armature by the insulation 75. The contact plate 74 is adapted to engage with, or be separated from, a pair of contacts 76 of an energizing circuit 77 of a signal device 78. In Fig. 8 the signal device 78 is shown as an audible signal device, but obviously a visual signal device may be employed if desired.

In the present showing, the electromagnet 71 is in a normally closed circuit, and the signal device 78 is in a normally open circuit. However, should it be so desired, the above conditions may be reversed.

Referring to Figs. 8 and 9, where the circuit controlling means for the electromagnet 71 is shown in two different positions, and to the other figures illustrating the means for rotating the impeller 42 in the proper direction and at the desired rate of speed, and assuming that the body of mercury 48, because of the rotation of the impeller 42, has a portion thereof, on one side of the adjusting block 52, raised to such a height in the impeller housing 30 as to have the contact screw 64 immersed therein. Incident to this operating condition of the device a differentiation "d" will have been established between the respective levels of the liquid bodies at the respective sides of the dam portion 52. (See Fig. 8.) Under such conditions the energizing circuit from the source of power 72 for the electromag-

net 71 will be completed between the contact screws 64 and 61. Electromagnet 71 will be energized, attracting its armature 73 and withdrawing contact plate 74 from engagement with the contacts 76 of the energizing circuit for the signal device 78 and such signal device will remain silent. This condition will prevail as long as the speed of rotation of the turntable 12 is maintained above a predetermined minimum.

Regulation of the orifice or gap between the adjusting block 52 and the face of the impeller 41 ensures that excess of mercury, above that required for the immersion of the contact screw 64, will flow back into the bottom of the impeller housing 30.

If, however, the speed of rotation of the turntable 12 falls below the required minimum, the mercury 48 will flow back to the bottom of the impeller housing 30 faster than it will be carried upwardly by the impeller 42. In this event the lowering of the level of the mercury 48 on the side of the adjusting block 52 where the contact screws 64 and 61 are located, with the result that eventually the mercury 48 will be no longer in engagement with the contact screw 64. Electrical engagement between the contact screws 61 and 64 is broken, thus breaking the energizing circuit for the electromagnet 71, which is thereupon deenergized, releasing its armature, which brings the contact plate 74 into engagement with the contacts 76. This completes the energizing circuit for the signal device 78, which thereupon operates to apprise an attendant that the speed of rotation of the turntable 12 and mechanism carried thereby, has dropped below the required minimum.

The invention has been shown and described as a means for operating a signal device when the speed of a machine falls below a certain required or specified minimum. It is applicable however, as a means for operating a signal device when the speed of a machine rises above a required or specified maximum. Also, the invention may be embodied in various forms, and therefore, the scope of the invention is not to be limited other than as pointed out in the appended claims.

I claim:

1. In combination with a sedimentation tank having a center pier, and a rotary sediment raking construction of the traction driven type having a traction driven arm member extending from the center to the margin of the tank, which member is rotatable about and having its inner portion supported upon said center pier, said center pier having fixed thereon at its upper end portion a turntable base, said rotary raking construction having a turntable to support the inner end of said arm member and rotatable upon said turntable base, a rotary speed responsive switch device supported by and mounted stationary with respect to said pier, and rotation transmitting means operatively interconnecting said turntable with said speed responsive device to cause the latter to rotate in proportion to the rotation of said turntable.

2. Apparatus according to claim 1, in which the speed responsive device has gear means for driving the same and in which the transmitting means comprise a ring gear connected and rotating coaxially with said turntable and meshing with said gear means of the speed responsive device.

3. Apparatus according to claim 1, in which the speed responsive device has gear means for

- driving the same, and the transmitting means comprising a ring gear connected and rotating co-axially with said turntable and meshing with said gear means of the speed responsive device, 5 in which further the turntable base is an annular element, and the ring gear and the speed responsive device are disposed substantially within in the space defined by the largest inner diameter of said turntable base.
- 10 4. In combination with a sedimentation tank having a center pier, and a rotary sediment raking construction of the traction driven type having a traction driven arm member extending from the center to the margin of the tank, which 15 member is rotatable about and having its inner portion supported upon said center pier, said center pier having fixed thereon at its upper end portion a turntable base, said rotary raking construction having a turntable to support the inner 20 end of said arm member and rotatable upon said turntable base, a rotary speed responsive switch device supported by and mounted stationary with respect to said pier, and rotation transmitting means operatively interconnecting said turntable 25 with said speed responsive device to cause the latter to rotate in proportion to the rotation of said turntable, said speed responsive device comprising a stationary chamber having electric circuit making or breaking terminals controlling a 30 circuit associated therewith, and adapted to receive and hold a bath of liquid electrical conductor, a scoop wheel having a shaft mounted in the wall of said chamber and having its lower portion immersed to a suitable degree in said liquid 35 conductor, said scoop wheel having a hub portion, a smooth rim portion, and evenly spaced radial wall portions between said hub and said rim portion, thus forming liquid transferring compartments between said radial wall portions, a bath 40 dividing dam construction extending transversely of said chamber and designed to conform to and

substantially hug the central vertical cross-sectional outline of the scoop wheel at least along the lower portion thereof, said dam being of sufficient thickness relative to the width and not narrower than the width of said scoop compartments to prevent unrestricted communication between both bath portions as defined by the dam construction, said dam construction, however, being designed to provide passage between both 10 said bath sections to permit a certain restricted and controlled predetermined rate of flow communication therethrough, said scoop wheel thus 15 potentially effective and depending upon its rate of rotation to transfer sufficient liquid from the one bath section to the other to effect a differentiation of the respective liquid levels in said bath sections to result in circuit making or breaking whenever the amount of liquid thus transferred from the one section past the dam construction exceeds said predetermined rate of return flow 20 communication to be dammed up sufficiently to influence said terminals and the circuit controlled thereby, and transmitting means for imparting rotation from said rotatable sediment raking construction to the scoop wheel of said 25 speed responsive device.

5. Apparatus according to claim 4, in which the scoop wheel is additionally defined as by a uni-lateral disc wall portion extending between the hub and the rim portion and the radial wall portions, thus forming laterally open cavities to 30 represent said scoop compartments.

6. Apparatus according to claim 4, in which the scoop wheel is additionally defined as by a unilateral disc wall portion extending between the hub and the rim portion and the radial wall portions, and in which the rim portion has a substantially cylindrical exterior surface and merges with the disc wall portion by way of a rounded 35 transitional portion.

CHARLES H. SCOTT.
